CLAIM

The ornamental design for a dental flosser, as shown and described.

DESCRIPTION

FIG. 1 is a front perspective view of the dental flosser of our new design;

FIG. 2 is a front end view of the dental flosser of our new design;

FIG. 3 is a rear end view of the dental flosser of our new design;

FIG. 4 is a top plan view of the dental flosser of our new design;

FIG. 5 is a bottom plan view of the dental flosser of our new design;

FIG. 6 is a left side view of the dental flosser of our new design; and,

FIG. 7 is a right side view of the dental flosser of our new design.

The broken lines in the drawings are for illustrative purposes only and form no part of the claimed design.
